United States Patent

Des. 237,032
Patented Oct. 7, 1975

237,032

STRAINER

Edward N. Montesi, Barrington, R.I., assignor to
Dart Industries Inc., Los Angeles, Calif.

Filed May 8, 1974, Ser. No. 467,990

Term of patent 14 years

Int. Cl. D7—04

U.S. Cl. D7—47

FIG. 1.

FIG. 2.

FIG. 3.

FIG. 4.

FIG. 5.

FIG. 1 is a top plan view of a strainer showing my new design;
FIG. 2 is a bottom plan view thereof;
FIG. 3 is a side elevational view thereof;
FIG. 4 is a front elevational view thereof; and
FIG. 5 is a rear elevational view thereof.

I claim:
The ornamental design for a strainer, substantially as shown.
